RECTANGULAR METAL CATHODE RAY TUBE

Stanley J. Koch, Clifton, and Robert E. Rutherford, Nutley, N. J., assignors to Allen B. Du Mont Laboratories, Inc., Clifton, N. J., a corporation of Delaware

Application March 13, 1950, Serial No. 149,342

1 Claim. (Cl. 220—2.3)

This invention relates to cathode ray tubes and more particularly to cathode ray tubes having a rectangular screen, a substantial portion of the tube blank being sheet metal.

It is desirable that a cathode ray tube for television have a rectangular face or viewing surface. The picture produced at the television transmitter in accordance with F. C. C. standards has a rectangular pattern having a width to height ratio of 4:3. In order to reproduce the entire picture on a cathode ray tube having a circular screen, it has been necessary to use only a rectangular portion thereof with the corners of the rectangular picture substantially at the edge of the circular screen. Conversely the tube may be operated so that a portion of the transmitted picture covers a large part or even the whole of the circular screen by suitable adjustment of the scanning apparatus of the receiver. In this latter event not all of the original picture is reproduced, since portions extend beyond the viewing surface of the tube. A compromise, therefore, between seeing the entire picture and using most or all of the screen, has been made. However, a tube having a rectangular viewing surface has long been desirable.

In recent years cathode ray tubes have been made having a glass neck portion, a glass viewing screen and a metal frusto-conical portion. One of the fundamental problems in the production of such tubes in which there is a relatively large glass to metal seal area is that of obtaining a metal having the same temperature coefficient of expansion as that of the glass. One such metal, and that which is popularly used, is an alloy of iron and chromium known and available on the market as 446 Chrome Iron, in which chromium comprises approximately 26% to 30% of a volume of the metal. This alloy may be hot rolled into sheets. It is not sufficiently malleable to be pressed or drawn into the shape required for use in a cathode ray tube. It is possible, however, to spin pieces cut from the sheets into circular cones.

Heretofore there has been no known method of producing a metal cathode ray tube having a rectangular face, and no structure has been known producing a commercially satisfactory product. The rectangular cone portion of the tube could neither be spun nor pressed out of the chrome iron.

Consequently, it is an object of this invention to provide an improved cathode ray tube and method of manufacturing such tube.

Another object is to provide a commercially practical metal cathode ray tube having an approximately rectangular face or viewing surface.

Other objects will be apparent after a study of the following specification, claim and drawings, in which:

Figure 1 is a perspective view of a cathode ray tube constructed in accordance with the invention;

Figure 2 shows the contour of the face plate of the tube of Figure 1;

Figure 3 is a side elevational view of the rectangular metal cone portion of the tube;

2

Figure 4 is a cross sectional view of the frustoconical die and the metal cone;

Figure 5 is a front or open end view of a circular metal cone showing preferred pressure points;

Figure 6 is an exploded view of the tool and die and resulting rectangular cone involved in one step of the method herein disclosed; and

Figure 7 is a view of the metal blank showing another step in the process.

Referring now to Figure 1, it may be seen that the metal rectangular cathode ray tube comprises a cone portion 11, a face plate 12 and a neck portion 13. The substantially rectangular face plate is shown in the front view of Figure 2. The cone portion 11 is made of a chrome iron alloy having the same temperature coefficient of expansion as the glass face plate 12, in order that there may be an airtight seal between the edge of the glass and the rim 14 of the cone. The electron gun structure is mounted in the usual way within the neck portion 13. The face plate 12 is the viewing surface for the tube.

The rectangular cone portion 11 is formed or made in the following way. A circular disc of chrome iron has an inner circular opening of desired radius of for instance, approximately 2½", so as to be joined eventually to the neck portion 13 of a cathode ray tube. This disc is then formed in the shape of the frustum of a circular cone by spinning on a lathe and forcing the annular portions between the inner and outer edges of the disc to conform to the contour of a circular conical die 16 shown in cross sectional representation in Figure 4. The circular cone identified at this stage by the numeral 111 has a rim 114 formed at the outer open end thereof as shown in Figure 4. This rim 114 is formed in the manner as heretofore known, so that the glass face plate of the tube may be sealed thereto.

The outer or open end portion of the cylindrical cone 111 next is subjected to a bending operation. Although we do not wish to be limited to any theoretical explanation, it appears that the spinning process increases the ductility of this 446 Chrome Iron thereby making it possible to bend rectangular-faced cones from circular cones. Preferably pressure for such bending operation is applied radially outwardly at four corners in the directions as shown by the arrows in Figure 5. These pressure points conform to the corners of the rectangular face plate or viewing surface having the approximate width to height ratio of 4:3. No pressure is applied to the lower constricted portion of the cone 11 so that this portion remains circular in cross section. The rim portion 114 of the cone 111 is bent carefully into the approximately rectangular shape desired, as illustrated in Figures 1 and 2.

The tool and die apparatus as shown in Figure 6 may be used in the bending operation. The die member 31 may have the shape as shown in Figure 6, being circular in cross section at the lower constricted portion thereof, with protruding portions at the corners of the upper portion thereof to exert pressure radially outwardly at the points shown in Figure 5. Thus when the cone is removed from the die 32 after being subjected to the pressure of the cooperating die member 31, it is in the desired rectangular form at the open end and circular at the inner or constricted end.

In order to insure the circularity of the constricted end of the cone 11 in spite of the deformation of the outer end of the cone 11, it has been found desirable to shape the cone 111 originally so that the in-turned flange at the constricted end will be an annular section of a flat disc instead of the frustum of a wide angle cone which is used in the prior art circular cross-section metal tubes and is shown in Figure 4. The necessity for strengthening the constricted end of the cone arises from the fact that the neck 13 is joined to the cone 11 by a

butt weld which has comparatively little strength. Therefore, atmospheric pressure on the substantially flat sides of the cone 11, after the tube has been evacuated, may bend the constricted end of the cone 11 sufficiently to break the glass-to-metal seal at that point.

For better results it is desirable that the rim 114 be somewhat thicker than the side portion of the cone such as for instance, .125" and .075". A glass face plate having the contour conforming to and of the same shape as the rim 14 of the rectangular cone may then be placed thereon and heated to cause the glass to melt and adhere by sealing thereto. This sealing operation is shown in Figure 7. It is preferred that a plurality of heating elements 28 be used so as to subject the rim of the cone and the edge of the glass plate to a uniform heating throughout the circumference thereof. The number of heating elements 28 to be used is not at all critical, but they should be placed uniformly around the rim. The heat is applied to the rim in the same manner as heretofore used in connection with circular cones and circular face plates.

It will be noted that in view of the bending operation, the edge or rim 14 of the rectangular cone 11 does not lie within a plane. The edges of the cone extend outwardly from the corners so as to form round surfaces both longitudinally and transversely of the rectangular rim. This shape is shown more clearly in Figure 3. The longer sides of the rectangle have a greater curve or hump than do the shorter sides in view of the greater length thereof.

The substantially rectangular face plate 12, therefore, should be formed in the same shape so as to conform to the shape of the rim. One of the principal sources of trouble in an all glass cathode ray tube having a rectangular screen has been that the comparatively flat sides of the rectangular cone are weaker from the standpoint of air pressure than are circular tubes. At the same time, the corners being rather sharp are subject to intense stresses. Consequently the glass cone must be made exceedingly thick. In the metal tube as described herein, by contrast, the metal cone is sufficiently flexible to bend slightly under air pressure, yet sufficiently strong to retain its primary or general shape. Furthermore, the corners of the rectangular metal cone are strong. Therefore, although the glass face plate 12 is 45 weaker to forces applied along the diagonal D of Figure 2, the metal cone 11 is stronger at this point and able to resist those forces. The face plate 12 is stronger with respect to forces applied in the direction indicated by the arrows H corresponding to the points where the 50 metal cone is weaker. Thus the rectangular metal cone 11 and the glass face plate 12 cooperate to form a rigid structure able to withstand the same forces as prior art cathode ray tubes of the same or similar size.

The following steps are involved in making complete 55 rectangular metal cathode ray tubes. The circular metal cone indicated at 111 is fabricated and thereafter formed by simple bending into the rectangular shape as indicated at 11. Thereafter, the cylindrical glass neck portion 12 is attached to the smaller or constricted end of the cone. 60 To accomplish this the cone 11 and the neck portion 13 may be mounted on a lathe and brought together in the presence of heat which melts the edge of the neck 13 joining the cone so that the two are sealed and formed into an airtight single or unitary piece. The face plate 65 12 may then be attached to the open end of the cone 11,

preferably by mounting the cone in a vertical position, that is with its rim 14 uppermost, and placing the face plate 12 in position to rest on the rim. A plurality of heating means 28, positioned about the circumference 5 of the rim 14 heats the rim, melting the edge of the face plate 12 and forming an airtight seal.

A tube blank for a rectangular cathode ray tube has thus been formed. The fluorescent particles may be applied to the glass face plate 12 or screen of the tube and the gun structure mounted within the neck portion 13, in accordance with well known methods and principles as used in prior art cylindrical tubes.

A rectangular metal cathode ray tube has been formed with a viewing surface having the 4:3 width to height ratio to accommodate the transmitted television picture. Essentially none of the picture is lost, while at the same time, essentially the entire screen of the tube may be used. A rectangular tube having a rim width of 16" and height of 12" will produce a picture having the same size as prior art circular screen tubes having a diameter of 20".

While modifications will occur to those skilled in the art, the scope of the invention is defined in the following claim.

25 What is claimed is:

A television tube envelope comprising a one piece continuous sheet metal tapering body, the lower end of said body having a circular opening therein, the upper end of said body being open and the walls about said opening defining an opening substantially rectangular in outline, the free marginal edges of said walls defining said opening being formed into a seating ledge of substantially rectangular configuration, each of the four sides of the substantially rectangular seating ledge being upwardly curved longitudinally thereof and coacting with each other to form a convexly curved seat for receiving a longitudinally and transversely convexly curved substantially rectangular viewing screen.
